(57) **CLAIM**

The ornamental design for a nozzle adapter as shown and described.

DESCRIPTION

FIG. 1 is a front, upper perspective view of a nozzle adapter showing our design;

FIG. 2 is a front, lower view thereof;

FIG. 3 is a front view thereof, the back view being a mirror image;

FIG. 4 is a first side view thereof, the opposing side being a mirror image;

FIG. 5 is a bottom view thereof; and,

FIG. 6 is a top view thereof.

The even-length broken lines depict portions of the nozzle adapter that form no part of the claimed design. The long-short broken lines depict boundaries of the design and form no part thereof.

1 Claim, 4 Drawing Sheets
